INSTRUCTION CUBICLE

Lawrence H. Power, 710 Leona Drive,
Ann Arbor, Mich. 48103

Filed May 26, 1969, Ser. No. 17,338

Term of patent 14 years

Int. Cl. D6—01

U.S. Cl. D33—7

FIG. 1 is a perspective view of the instruction cubicle embodying the inventive design;

FIG. 2 is a front elevational view of the cubicle;

FIG. 3 is a top plan view of the cubicle;

FIG. 4 is a left side elevational view of the cubicle;

FIG. 5 is a right side elevational view of the cubicle; and

FIG. 6 is a rear elevational view of the cubicle.

I claim:

The ornamental design for an instruction cubicle, as shown.
